INVENTOR.

Frederick R. Cutter.

UNITED STATES PATENT OFFICE.

FREDERIC R. CUTTER, OF SOMERVILLE, MASSACHUSETTS.

WATCH.

SPECIFICATION forming part of Letters Patent No. 341,095, dated May 4, 1886.

Application filed February 4, 1886. Serial No. 190,657. (No model.)

To all whom it may concern:

Be it known that I, FREDERIC R. CUTTER, of Somerville, in the county of Middlesex and State of Massachusetts, have invented a new 5 and useful improvement in Watches, of which the following, taken in connection with the accompanying drawings, is a specification.

My invention relates to a device for an easy adjustment of the end bearings of the arbor 10 of the balance-wheel of a watch. It is well known to all watch-makers that it is very nice and sometimes almost weary work to so accurately adjust the end bearings of the balance-arbor that there shall be no more end- 15 shake than required for the free movement of the balance-wheel. The object is to obtain the desired result by leaving a kerf either between the upper part of the rear portion of the balance-cock and its lower part, or be- 20 tween the rear part of the balance-cock and the plate to which it is attached. This object I obtain by the mechanism shown in the accompanying drawings, in which—

Figure 1 is a view of the rear plate of a 25 watch having my device attached. Fig. 2 is a side elevation of a watch, the rear plate of which is exposed, so as to show more clearly the application of my invention; and Fig. 3 is a section taken on line *y y* of Fig. 1, being 30 very much enlarged, so as to show more clearly the details of my invention.

In the drawings, A, Figs. 1 and 2, represents the outside case of a watch of the ordinary construction, and B one of the plates, 35 said plate being of the construction shown in the accompanying drawings, or of any other usual construction.

My invention does not relate to the plate of a watch, but solely to the device for adjust- 40 ing the part or parts that control the end-

shake of an arbor, E, therefore I need not explain in full all the parts of a watch, but shall explain and describe only such parts as form a part of or an adjunct of my invention.

C C is the part that is called the "balance-cock," and is made in the usual manner, except that its rear part, C, has a kerf, K, (see Figs. 2 and 3,) said kerf extending well back into the rear part of the balance-cock, as shown in Fig. 3. The use of this kerf K may be explained as follows: The balance-cock C C is attached to one of the plates of the watch by the screw S, Figs. 1 and 3, and, being kerfed, as has already been described, is provided with one or more set-screws located at or 53 near T, Figs. 1 and 2.

The set-screw T serves simply to gage the opening of the kerf K, while the screw S serves to hold the balance-cock to the plate, and also to compress the kerf K, and thus tend to bring 60 the part C (that is the part that governs the position and end-shake of the arbor of the balance-wheel) toward or against the end of the arbor; hence by using both screws, respectively, the most infinitesimal movement 65 may be imparted to the part C, that holds the end of the arbor of the balance-wheel. In other words, a perfect adjustment of the parts that control the end-shake may be made with certainty and rapidity. 7c

I claim—

In a watch, the combination of the kerfed balance-cock C C, having holding and adjusting screws S and T, with plate B and arbor E, all operating together substantially as 75 described, and for the purpose set forth.

FREDERIC R. CUTTER.

Witnesses:
